JOHN CLIFFORD HUGHES, OF MIDDLETOWN, NEW YORK, ASSIGNOR TO THE BORDEN COMPANY, OF NEW YORK, N. Y., A CORPORATION OF NEW JERSEY.

METHOD OF AERATING LIQUESCENT MATERIAL AND APPARATUS IN AID THEREOF.

1,411,103.

Specification of Letters Patent.

Patented Mar. 28, 1922.

Application filed March 21, 1921. Serial No. 454,276.

To all whom it may concern:

Be it known that I, JOHN CLIFFORD HUGHES, a citizen of the United States, and a resident of Middletown, in the county of 5 Orange and State of New York, have invented a new and useful Method of Aerating Liquescent Material and Apparatus in Aid Thereof, of which the following is a specification.

10 My invention relates to the incorporation of air, or other gas, and its extremely minute subdivision in what I term liquecent, or semi-liquid, i. e. more or less viscous liquid, material for example concentrated milk, 15 during its conversion for drying purposes into such an "aerated batter," or "aerated, coherent, plastic, adhesive mass," as described in United States Letters Patent No. 1,233,446 and 1,250,427, to Charles H. Campbell, and the objects of my invention comprise provision of a method, and means in aid thereof, whereby the air can be more rapidly, certainly, effectively and economically incorporated and more minutely subdivided, and with less risk of injuring the material,—particularly the milk. I attain these objects by treating, and by aid of apparatus, as hereinafter described, reference being had to the accompanying drawings, 30 in which:

Figure 1 is a diagrammatic, partly cross-sectional, view, suggestive of the conformations imparted to, and movements of, the material during practice of my method;

35 Figure 2 is a central longitudinal vertical cross-section of my above referred to preferred apparatus;

Figure 3 is a cross-sectional view on the line 3—3 of Figure 2 seen in the direction of the arrow; and

40 Figure 4 is a fragmentary section on the line 4—4 of Figure 2, and viewed in the direction of the arrow.

Figure 4^a is a detail end view showing 45 means for rotating the shafts.

My method is practised by moving, i. e. propelling portions of the material, for example milk which has been concentrated, say, preferably, from about four volumes 50 down to one volume, in a continuously onwardly moving stream around one of two longitudinally extended mutually parallel, substantially horizontal, imaginary axes, and, simultaneously, other portions of said

material in another similar, similarly moving stream around the other of said axes, the said axes being so approximated to each other that said streams are obliged to commingle with each other while they are moving between said axes. The effect of so manipulating the material is to impart to the respective portions thereof a, to an extent, whorl-like, or partially cylindrical, conformation approximately concentric with one of said axes, and containing, I believe, 55 longitudinal centrifugally produced interior air-spaces surrounding said axes, and through the relatively pervious, or open, ends of which spaces more or less air is sucked in to rise through the superimposed 60 portions of the whorl, thus contributing to 65 aeration as per United States Letters Patent No. 1,308,904.

Figure 1 of the drawings is an attempt to pictorially elucidate the streams, or rudimentary whorls, of the material, their partially cylindrical conformation, and their contained longitudinal air spaces. In said figure R represents a cross-section of the receptacle, or tank, hereafter described; A A' 70 the respective above referred to axes of the circular movements; S S' the air spaces. The jagged lines O O' represent the approximate exterior and interior boundaries of the whorls, the arrows within said boundaries 75 indicating suggestively the directions of movement of the material in the whorls, and in the zone between the axes where the respective streams commingle. P in said figure indicates a segregated stream of the material which, in the preferred practice of my 80 method, I continuously downpour toward between the said axes. In said zone the commingling of the streams causes multitudinous collisions between different portions 85 of the material, and of therein occlusions of air, particularly of those which are there moving in opposite directions; the result being continuously occurring multiple dislocations amounting often to localized cleav- 90 95 100 ings of the material and its occlusions, thus, as is of great importance, constantly and rapidly subdivided existing air spaces, or forming new ones.

The upper exterior surfaces of the whorls 105 being exposed to the atmosphere, and of more or less rough or porous character, and rapidly rotating, also catch and hold air

which passes into the body of the centrifugally tensioned material owing to its greater specific gravity, and similarly my above referred to downpoured stream of the material 5 collects air and conveys it into the mass beneath.

My operation is continuous, the rate of production of the final aerated product being proportional to the infeed of the material 10 as by my downpoured stream, and the product constantly rising to above the whorls in proportion to its aeration and resulting levitation and being constantly withdrawn by overflow, i. e. from a location which is at 15 least above the axes of the whorls.

I have also discovered it to be of advantage, if not essential, to cool the material during the continuance of the operation.

My above referred to preferred apparatus 20 in aid of the working of my above described process comprises a receptacle, R, for housing the operation. It is, preferably, of the conformation shown in the drawings, i. e. longitudinally extended, having mutually parallel, substantially vertical, longitudinally-extended, major sides, and similar, though shorter, ends. It is interiorly concavely curved along its longitudinal corners R' R' so as to there avoid angular material-collecting space, and particularly to, 25 as is also of advantage, present interior surfaces complementary to the external contours of the above described whorls of the material. I, preferably, provide the receptacle 30 with a removable cover R², though that is not essential. If a cover is used, it is provided with an opening, R³, to accommodate my downpoured stream P of the material, this opening being centrally located as shown 35 so that the material may be impelled by gravity towards between the axes of the whorls (Fig. 1).

In the ends of the receptacle I mount a pair of rotatory mutually parallel shafts 5, 45 5', having their axes in substantially the same horizontal plane, and each carrying, as shown, a plurality of alike ranks of therefrom radially projecting spaced-apart alike fingers, 6, 6, the fingers on one shaft being, 50 as shown, staggered relatively to the fingers of the other shaft, so that the fingers of the one may, during rotation, interpass the fingers of the other shaft.

I prefer to, as is important for my purpose, make the fingers of substantially rectangular cross-section, their propulsion of the material being thereby increased, and I also preferably locate them so that respective fingers of the respective shafts shall have little 60 more than a fair clearance when interpassing each other. I project the fingers from each shaft as far as is consistent with their ends clearing the other shaft and the sides of the receptacle, the shafts also being correspondingly located and preferably concen- 65

trically with the said curvatures of the interior of the receptacle.

I provide, of course, any convenient means for imparting to the shafts simultaneous and synchroneous rotation, and preferably 70 in the same circular direction, thereby causing their respective fingers to interpass each other from opposite directions, but my method is operable although the shafts be rotated in opposite circular directions. 75

Such means for so rotating such shafts from a source of power seem too well known to require other description than afforded by Figures 2 and 4^a, showing gears 7 7' carried respectively by the ends of the shafts 5 5' 80 outside of the receptacle R, and within a usual casing, R⁴, a gear 8' meshing with said gears 7 7' and carried by a superdisposed power shaft 8, carrying a pulley 9 operated by aid of a belt 10.

It is of advantage, though not absolutely essential, that the elements above referred to be so adjusted relatively to each other as to insure that the ranks of the fingers carried by the respective shafts shall so interpass 90 each other as that both shall be, at the moment, in substantial parallelism with each other, and in the plane in which the shafts are, as aforesaid, located, a much more desirable effect being thereby produced on the 95 material and its gaseous occlusions.

Within the receptacle adjacent the end thereof opposite to that near which I downpour the material, is provided a conduit 12 for the final aerated product, the said conduit having, as is important, all lips of its inlet, or intake, opening 13 located in a horizontal plane above the axes of the shafts, the said lips being thus presented upwardly to the levitating, thereover flowing, aerated 105 material, and the said conduit extending from said opening downwardly within the receptacle so as to afford therein a direct downward gravity fall of the product as it overflows said opening. The conduit is 110 provided adjacent the bottom thereof with an outlet 14.

I provide any well known convenient means for imparting to the material, during the operation of my method, a temperature 115 lower than normal, for example a usual jacket 15 for the receptacle, as indicated by dotted lines in the drawings, and having the usual connections and appliances required for forcing a current of cooling fluid, air or 120 water, through the jacket.

Operation: rapid rotation is imparted to the shafts and continuously maintained throughout the operation, the speed being variable according to the nature of the material and at the rate of about 300 revolutions per minute in the case of concentrated milk. The material is then admitted in a constant stream, preferably downwardly 125 poured, as above described, and from adja- 130

cent that end of the receptacle which is opposite the outlet. The rotating fingers immediately pick up the material and as it accumulates impart thereto the whorl-like 5 quasi-cylindrical conformations above described. The fingers advance through the moving material more rapidly than the material is progressing and thus are constantly opening behind them in the material a wake 10 of displacements or openings into which more or less air is sucked. When respective ranks of the fingers interpass each other the material and its gaseous occlusions are thereby greatly agitated and the latter subdivided indefinitely and meanwhile additional supplies of air are, I believe, indrawn through the cylindrical air spaces within the whorls. As the material becomes sufficiently aerated it will rise by levitation above the 15 whorls and overflow the said lips of, and thence down, the outlet conduit from the bottom of which it is removed to be dried or otherwise further treated as desired, the resulting aerated, coherent, plastic, adhesive, 20 mass of previously concentrated milk being thus continuously, progressively, separated, from the comparatively unaerated remainder, by aid of levitation and gravity and without interrupting the continuity of the 25 30 operation or being remingled with comparatively unaerated material.

The rate of infeed is, preferably, regulated so as to prevent any substantial accumulation of unbeaten material, the latter being promptly picked up by the fingers as it enters the receptacle, and proportionately to its increasing aeration progressively spirally moved onwards towards the outlet, thereby avoiding the hitherto undesirable return of 40 partially aerated material into an underlying accumulation, or pool, of unaerated. This desirable result appears to me unattainable unless my above described duplex 45 mutually intercepting whorls located in the same horizontal plane be so employed, the constituent material of each being, at the time of interception, aerated to substantially the same degree.

Having now described my invention, what 50 I claim as new and desire to secure by Letters Patent is the following, viz:

1. In the treatment of liquefied, semi-liquid, viscous lacteal material to aerate it, the steps which consist in downwardly pouring a continuous stream thereof, dividing 55 said stream and continuously propelling parts thereof circularly around an axis extending one side of and angularly to the direction of said stream, simultaneously similarly propelling other parts thereof around another similar axis parallel with the first axis and extending on the opposite side of said stream, and meanwhile, by aid of gravity, continuously, progressively, from 60 a location above said axes, withdrawing the

aerated material and separating it from less aerated.

2. In the treatment of liquefied, semi-liquid, viscous lacteal material to aerate it, the steps which consist in downwardly pouring a continuous stream thereof; dividing 70 said stream and continuously propelling parts thereof circularly around an axis extending one side of and angularly to the direction of said stream; simultaneously similarly propelling other parts thereof around another similar axis parallel with the first axis and extending on the opposite side of said stream; by aid of gravity continuously, 75 progressively, from a location above said axes, withdrawing aerated material and separating it from less aerated, and meanwhile cooling the material while it is being thus treated.

3. The method of treating milk to convert 80 it into an aerated, coherent, plastic, adhesive, mass which comprises first concentrating it; and then propelling portions of the resulting concentrate in a stream moving circularly around one of two mutually parallel longitudinally extended imaginary axes both located in substantially the same horizontal plane; simultaneously similarly moving other portions of said concentrate in another similar stream around the other of said 85 axes; commingling portions of said streams with each other while they are moving between said axes; and meanwhile, by aid of gravity, continuously progressively withdrawing the aerated concentrate from above 90 said axes.

4. The method of treating milk to convert 95 it into an aerated, coherent, plastic, adhesive, mass which comprises first concentrating it; next, pouring a continuous stream 100 thereof downwardly towards between two mutually parallel axes located in a substantially horizontal plane; next, dividing said stream and propelling portions of it in a stream moving circularly around one of said axes and simultaneously propelling other portions in another similar stream around the other of said axes; and, meanwhile, by aid of gravity, continuously progressively withdrawing the aerated concentrate from 105 above said axes.

5. In an apparatus for aerating semi-liquid material, a receptacle, and within said receptacle a pair of rotatory mutually parallel shafts having their axes in substantially 110 the same horizontal plane and each carrying a plurality of alike ranks of therefrom radially projecting spaced-apart alike fingers, the fingers of the one shaft being extended and staggered relatively to the fingers of 115 the other shaft so as to interpass each other, the shafts and ranks so disposed that the fingers while interpassing are simultaneously momentarily in the same plane, means to simultaneously rotate said shafts and 120

means to meanwhile by aid of gravity withdraw aerated material from a location in said receptacle above said axes.

6. In an apparatus for aerating semi-
5 liquid material, a receptacle, and within said receptacle a pair of rotatory, mutually parallel, shafts having their axes in substantially the same horizontal plane and each carrying a plurality of alike ranks of therefrom radially projecting spaced-apart alike fingers of substantially rectangular cross section, the fingers of the one shaft being extended and staggered relatively to the fingers of the other shaft so as to interpass each other,
10 15 the shafts and ranks so disposed that the fingers while interpassing are simultaneously momentarily in the same plane, means to simultaneously rotate said shafts and means to meanwhile by aid of gravity withdraw aerated material from a location in said receptacle above said axes.

7. In apparatus for aerating semi-liquid material, a receptacle therefor, a pair of substantially horizontally longitudinally extended, mutually parallel, finger-carrying, 25 shafts rotatably mounted in said receptacle; means to rotate said shafts simultaneously; means to direct a downpouring continuous stream of the material towards the middle 30 of the interspace between the shafts adjacent one end thereof while they are rotating, and means adjacent the opposite end of the shafts to meanwhile continuously progressively withdraw the aerated material from 35 the receptacle through an opening located above the shafts.

8. In apparatus for aerating semi-liquid material, a receptacle therefor, a pair of substantially horizontally longitudinally extended, 40 mutually parallel, finger-carrying, shafts rotatably mounted in said receptacle; means to rotate said shafts simultaneously; means to direct a downpouring continuous stream of the material towards the middle 45 of the interspace between the shafts adjacent one end thereof while they are rotating,

and means comprising a conduit having an upwardly presented intake opening and extending downwardly within the receptacle adjacent the opposite end of the shafts to meanwhile continuously progressively withdraw the aerated material from the receptacle.

9. In apparatus for aerating semi-liquid material, a receptacle therefor, a pair of substantially horizontally longitudinally extended, 55 mutually parallel, finger-carrying, shafts rotatably mounted in said receptacle; means to rotate said shafts simultaneously; means to direct a downpouring continuous stream of the material towards the middle of the interspace between the shafts adjacent one end thereof while they are rotating, and means adjacent the opposite end of the shafts to meanwhile, by aid of gravity, progressively continuously withdraw aerated material from the receptacle, said last mentioned means comprising a conduit extending 60 downwardly within the receptacle and having an inlet opening the intake lips of which are presented upwardly in a plane at a level above that of the axes of the shafts.

10. In apparatus for aerating semi-liquid material, a receptacle therefor; a beater within the receptacle; means to rotate the beater; and means, comprising a conduit having an upwardly presented intake opening and extending therefrom downwardly within the receptacle, to meanwhile withdraw aerated material therefrom by aid of 70 gravity.

11. In apparatus for aerating semi-liquid material, a receptacle therefor; a beater within the receptacle; means to rotate the beater; and means, comprising a conduit having an upwardly presented intake opening and extending therefrom downwardly within the receptacle, to meanwhile withdraw aerated material therefrom by aid of 75 gravity from a location above the axis of 80 rotation of said beater.

JOHN CLIFFORD HUGHES.
